INERTIA DEFEATING FILM REEL

Morris Goldberg, Denver, Colo., assignor to Goldberg Brothers, Inc., Denver, Colo., a corporation of Colorado

Filed Dec. 26, 1967, Ser. No. 9,932

Term of patent 14 years

U.S. Cl. D61—1
Int. Cl. D16—07

FIG. 1.

FIG. 2.

FIG. 3.

FIGURE 1 is a top plan view of the inertia defeating film reel showing my new design, the bottom being substantially identical thereto;

FIGURE 2 is an edge view thereof; and

FIGURE 3 is a cross sectional view through the reel with portions broken away to conserve space.

I claim:

The ornamental design for an inertia defeating film reel, as shown and described.
